UNITED STATES PATENT OFFICE.

ALBERT A. MACLEOD, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,401,167.

Specification of Letters Patent. Patented Dec. 27, 1921.

Application filed April 7, 1917. Serial No. 160,535.

To all whom it may concern:

Be it known that I, ALBERT A. MACLEOD, a citizen of the United States, residing at Swampscott, in the county of Essex and State of Massachusetts, have invented certain Improvements in Lasting-Machines, of which the following description, in connection with the accompanying drawings, is a specification, like reference characters on the drawings indicating like parts in the several figures.

This invention relates to lasting machines and is herein illustrated as embodied in a machine for lasting stitch-down shoes. The machine in which the invention is shown as embodied, by way of example, is of the type disclosed and claimed in United States Letters Patent No. 1,117,087, granted November 10, 1914, on application of Adam H. Prenzel and embodying also the improvement disclosed and claimed in United States Letters Patent No. 1,209,666, granted December 26, 1916, on application of Louis M. Brown, and in application Serial No. 44,915, filed August 11, 1915, by Matthias Brock. The invention comprises also a method of lasting shoes, which method may be most conveniently practised with the aid of the machine of the related invention herein disclosed.

The marked increase in the cost of upper leather has caused more attention to be paid to the use of canvas and other fabrics for shoe uppers as substitutes for leather, particularly in the more moderate priced shoes.

The simplicity and cheapness of the stitch-down method of shoemaking have attracted manufacturers to this method in connection with fabric uppers, but a difficulty has been encountered in that the outturned margin of the upper when of fabric cannot be satisfactorily trimmed and finished to correspond with the edge of the sole and welt, when a welt is used, the edge face of the fabric having a texture and color in contrast with the leather or rubber of which the sole is composed.

A general object of this invention is to improve machines for lasting stitch-down shoes, and a more specific object is to provide in a machine of the above type means for so handling the outwardly extending margin of the leather or fabric upper material of the stitch-down shoe as to avoid trimming off the material and so as to form a finished edge

of neat appearance and one such that the use of a welt in attaching the outsole is unnecessary.

A feature of the invention consists in means arranged adjacent to the sole supporting face of the work support by which the outwardly extending margin of an upper may be held against the edge face of the innersole and means, for example a lasting tool, for forcing the upper, which tends to bridge the angle between the side of the last and the projecting margin of the sole, into the said angle and against the top face of the projecting margin of the sole. Preferably the remainder of the projecting margin of the upper, which extends beneath the edge face of the sole, is folded under the projecting margin of the sole and against the bottom face of the inner sole so that it will be invisible in the completed shoe.

As shown herein, an abutment is provided opposite the edge face of a sole resting on the support, the said abutment being adapted by contact with the margin of the upper to hold the upper against the edge face of the sole while the upper is forced by a lasting tool, for example the nozzle of a stapling mechanism, into the angle between the side of the last and the projecting margin of the sole to be secured by cement or staples. The part of the upper which projects beyond the edge face and is bent inwardly under the bottom of the projecting margin of the sole is held by the work support against the bottom of the sole.

It is desirable to provide an effective surface for pressing the margin of the upper against the lower face of the projecting margin of the sole. A further feature of the invention consists, therefore, in means which forms a raised surface above the general level of the sole supporting face of the work support. As shown herein, this means comprises a plate constructed and arranged to provide a pressure surface by which the portion of the upper which is bent under the projecting portion of the sole may be firmly pressed against the sole bottom, the plate being so constructed and arranged as not to interfere with the securing of the upper by inserted fastenings when desired. The abutment and pressure surface coöperate, in the construction shown, with the nozzle of a stapling mechanism to force the upper

tightly into the angle between the side of the last and the projecting margin of the sole and to press the outwardly extending margin of the upper firmly against the top 5 face of the projecting margin of the sole, while the abutment acts to press a portion of the outwardly extending upper against the edge face of the sole and the pressure plate acts to press the remaining portion of 10 the margin of the upper against the lower face of the projecting margin of the sole. Either or both of the engaging surfaces of 15 the upper and the projecting margin of the sole may be coated with cement so that the upper will be held in the position into which it is worked in the operation of the machine and fastenings may be employed to any desired extent further to secure the upper in lasted position in the angle between the side 20 of the last and the projecting margin of the sole.

A further feature of the invention consists in an abutment and pressure plate so mounted that they may be swung into an inoperative position when the machine is being used 25 for staple lasting in the usual manner.

It is important that the cemented surfaces 30 between the upper and the top and bottom face of the projecting sole margin be very firmly forced together between the face of the nozzle and the pressure plate on the work support. As shown herein, manually operated means is provided for effecting relative movement between the lasting 35 tool or nozzle and the pressure plate to produce this pressure. Since the repeated operation of the work support to effect this pressure is fatiguing to the operator, it will be difficult by that means to 40 secure uniform and adequate pressure at each operation.

A further feature of the invention consists, therefore, in the combination with the lasting tool and abutment or pressure plate, or both said abutment and pressure plate, 45 of means for effecting relative movement between the lasting tool and abutment or abutment and pressure plate which is operable at the will of the operator either manually 50 or by power. In the construction shown, after the operator has partially raised the work support manually he may, if he so desires, cause the work support to be lifted by power the remainder of the distance and 55 forced upwardly by uniform pressure to hold the work between the lower face of the lasting tool and the pressure plate of the work support. The power operation is effected by pressure upon a treadle in a plane 60 slightly below the treadle which operates the shoe support manually.

The lasting tool as herein shown forms 65 also the nozzle of a fastener inserting mechanism, for example, a staple forming and inserting mechanism, and a further feature

of the invention consists in means for rendering the fastener inserting mechanism inoperative when power operation of the machine is required only to secure the adhesion of cemented surfaces of the upper 70 and sole without insertion of fasteners. As herein shown, means is provided which may be set by the operator to render the wire feed rolls of the staple forming mechanism inoperative, for example, by separating the 75 wire feed rolls so that they cannot grip and feed the wire.

Although in the above consideration of the invention special emphasis has been laid upon use of the machine for lasting shoes 80 provided with upper margins which may be worked over the edge face of the sole and against the bottom of the sole margin and secured by cement, it is to be understood that certain advantages of this invention 85 may be secured in connection with lasting shoes having uppers only ample enough to engage the edge face of the sole while bridging the angle between the side of the last and the projecting margin of the sole. 90 In this event the abutment may be used with good results to hold the edge portion of the upper while the portion between the portion held and the last is being worked into the angle by the lasting tool, a short upper being 95 withdrawn from contact with the abutment if necessary to provide stock enough to line the angle. Inserted fastenings may be employed to secure the upper in lasted position with or without the use of cement additionally to hold the upper, or cement only may be used.

A further object of the present invention is an improved method of making shoes, especially applicable to the manufacture of 105 stitchdown shoes, in which cement is applied to the marginal portion of the shoe upper or to the marginal portion of the sole or to both marginal portions, and in which the upper is progressively shaped to the last by 110 wiping it down over the side of the last and secured, as the shaping progresses, by forcing the marginal portion of the upper into close contact with the marginal portion of the sole to cause firm adhesion of the marginal portions of the upper and sole. In 115 practice, the marginal portions of the upper and the sole will be forced progressively into close contact with each other simultaneously with the termination of each wiping operation. In some classes of work it will be found desirable to insert fastenings along certain portions of the shoe upper to 120 act as additional securing means and to cooperate with the cement in holding the cemented surfaces firmly together.

These and other features and objects of the invention will be apparent from the following detailed description when read in connection with the accompanying draw- 130

ings, and the various novel features of the invention are set forth in the appended claims.

In the drawings,

5 Figure 1 is a front elevation of the machine, part of the column being broken away;

10 Fig. 2 is a perspective view of the nozzle and work support with the sole edge abutment and pressure plate in operative position;

15 Fig. 3 is a side view of the mechanism shown in Fig. 2 and showing the shoe in section with its upper being operated upon to last the upper and press the margin of the upper about the edge portion and bottom of the sole; and

20 Fig. 4 is a plan view showing in dotted lines the abutment and offset filling plate swung into inoperative position.

The illustrated machine comprises staple forming and inserting mechanism including a lasting tool which serves also to guide the staples into position to secure the shoe 25 upper in lasted position, and a work support comprising a sole rest upon which the sole of the shoe to be lasted is supported, the work support being movable toward the lasting tool to cause said tool to effect the 30 upper stretching and wiping operations.

The illustrated staple forming and inserting mechanism comprises a driver bar 16 (Fig. 1) lifted against the action of a spring 18 by a lifting cam 20 acting upon 35 a block 22 upon said driver bar. Feed rolls 24, 36 are operated by connections to a slotted lever 26 which in turn is rocked by a cam operated lever 28.

Mechanism is provided for feeding the 40 wire *w* which forms the staples to the staple forming mechanism and cutting the wire. The release of the wire for the return movement of the feed rolls 24, 36 is effected during the wire cutting operation by the action 45 of a plunger 30 which engages an adjustable stop 32 on a lever 34 which carries the co-operating presser roll 36. A spring 38 operates to maintain the presser roll 36 yieldingly in pressing relation to the feed roll 24. 50 During the cutting operation the action of the plunger 30 upon the stop 32 rocks said lever 34 about its fulcrum 40 and moves the roll 36 toward the left out of pressing relation to the roll 24.

55 The wire *w*, which is preferably comparatively fine, is wound upon a spool 46 which turns upon a stud 48 upon a bracket 50 carried by the machine head. To prevent too rapid unwinding of the spool and also to 60 prevent the tension on the wire from pulling the wire down into the lower coils of the spool, thus causing it to kink or tangle, a take-up device is provided which comprises a grooved wheel 52 carried by a spring supported plunger 54 guided through a spring

socket 56 and limited in its downward movement by a pin 58 traveling in a slot in said socket, which also prevents the plunger from turning in its socket. When the wire *w* is suddenly fed forward by the feed rolls, the 70 spring plunger 54 will yield sufficiently to allow enough wire for a staple to be fed without necessarily overcoming the inertia of the spool 46 and without pulling the strand of wire down between the coils on 75 the spool. When the spring plunger 54 reacts, the spool 46 is slowly turned to supply the wire for the next staple. A work support 78 is carried upon a rod 66 guided for vertical movement in guides 68, upon brackets 70 attached to the column 72 of the machine. The work support 78 has an inclined face 74 provided with a staple clenching stud 76. The face 74 is formed upon a segmental block 78 guided for adjustment 80 about an axis lying in the clenching face of the stud 76 and is held in its different positions of angular adjustment by a clamp 82 held by a cap screw 82. Preferably also the segmental block 78 is mounted for horizontal 90 adjustment by means of a dovetailed connection 84 held in a split clamp block 86 by screws 88, 90. The screw 90 is extended to provide a connection for one end of a spring 92 which tends to move the work 95 support back to its lowermost position and against which the support is raised by pressure upon a treadle 94 or by power in a manner to be described.

A lasting tool 100 is formed to present 100 to the side of the last a smooth upper wiping face 102 inclined to the direction of relative movement of the tool and work support at a sharply acute angle, the tool 100 having upon its rear side a flat face 104 approximately parallel to the direction of staple drive. Through the tool 100 is a staple guiding passage 105 arranged to deliver a 105 staple as close to the wiping face 102 as is consistent with proper strength of the wall 110 of the passage. The inclination of the wiping face 102 and the direction of relative movement of the tool 100 and the sole support preferably approach parallelism as closely as may be without unduly weakening the walls of the staple guiding passage. The tool 100 is provided with an end clamping face 106 adapted to hold the upper down and press it out upon the margin of the sole, and preferably this end face is so inclined relatively to the wiping face 102 that during the upper wiping and stretching operation the end face 106 will press upon the upper overlying the sole margin substantially throughout the extent of said end face, 115 the face being of sufficient extent to engage and press the upper overlying the sole margin substantially from the last to the edge of the sole. The clamping face 106 may be smooth or provided with corruga- 120

125 130

tions or teeth to prevent the upper from slipping too easily over the clamping face during the wiping and stretching operations. The work support should be so adjusted that 5 the face 74 will be substantially parallel to the clamping face 106 of the lasting tool or presser member 100 so that the said faces will coöperate to clamp the marginal portion of the upper upon the sole.

10 The illustrated mechanism for raising the work support manually or by power is the same as that described and claimed in the application above referred to. Depression of the treadle 94 operates a lever 130 to move the rod 66 longitudinally upward and raise the work support. After the treadle 94 has been partly depressed the foot of the operator is in a convenient position to depress a starting treadle 96 if he so desires. When the treadle 96 is depressed a rod 132 is moved downwardly by a cam on the main shaft of the machine and through a spring 134 presses upon the rear end of a rearwardly extending arm 136 on a rock 15 shaft 138. Mounted upon the rock shaft are downwardly extending arms 140 which are connected at their lower ends to forwardly and rearwardly moving wedge members 146 which may slide under rolls 148 mounted on opposite sides of the rod 66 when the rod is partially raised. As the wedges 146 are driven under the rolls 148 by the reaction of the spring 134 the work support is forced upwardly and the cemented surfaces are forced together as by 20 a hammer blow and strongly clamped between the face 106 of the tool 100 and a pressure plate 112, whereby firm adhesion of the cement is assured.

25 30 35 40 45 50 55 60

In the power operation of the machine for effecting pressure upon the work without driving staples, it is necessary to render the stapling mechanism inoperative. This is effected, in the construction shown, by a hand lever 42 by manipulation of which a lug 44 is brought against a stationary portion of the machine to separate the feed rolls 24, 36 and maintain them in separated relation against the spring 38 and prevent feeding of the wire.

The segmental block 78 is provided with a rearwardly projecting lug 110 to which is rotatably secured the pressure plate 112 by means of a screw 114. The screw has a portion equal in length to the thickness of the plate 112 through which it passes freely and has a smaller threaded portion which is threaded into the lug 110. The forward portion of the plate 112 is only thick enough to raise the surface of the work support 74 to the height of the clenching stud 76 so that a smooth work supporting face will be provided on the work support for the portion of upper bent under the sole. A space is provided between the 65 end of the plate 112 and the stud 76 so as to permit the setting of staples if desired while the plate 112 is in operative position, and a pin 118 is provided in the lower face of the plate which engages the block 78 70 and prevents movement of the plate beyond its operative position. The plate is maintained yieldingly in operative position by a spring plunger 116 which engages a suitable recess on the lower face of the plate 75 112. To the upper face of the plate 112 is adjustably secured an edge abutment 120 by means of a screw 122 which passes through a slot in the abutment and is threaded into the plate 112. The abutment 80 120 is also provided with a slot to accommodate the head of the screw 114, the slots permitting adjustment of the abutment toward and from the edge of the sole. The abutment has a face 121 perpendicular to 85 the plate 112 and of approximately the height of the thickness of the sole and two thicknesses of upper, and above that face has a face 123 parallel with the face 104 of the lasting tool 100. The face 123 prevents 90 catching of a fold of the upper between the abutment and lasting tool and coöperates with the face 104 to form a square angle at the top corner of the sole edge face and with the plate 112 to form a square angle at the 95 bottom corner of the sole edge face.

In one manner of operating the machine for lasting a stitch-down shoe, the lever 42 is operated to permit the rolls 24, 36 to engage and feed the wire and the pressure plate 100 112 and abutment 120 are swung about the screw 114 into the dotted line position shown in Fig. 4 out of the way to allow staple lasting of the upper at various points in the usual manner. The upper, having had the 105 marginal portion of its inner face coated with cement, is drawn over the last more or less tightly by the fingers of the operator and several staples are driven about the periphery of the shoe through the upper and 110 innersole close to the edge of the last, the number of staples and the location being determined by the nature of the work and the judgment of the operator. The number of staples used is preferably only sufficient to 115 hold the upper in proper position upon the last to prevent its being displaced by the subsequent lasting operations. The lever 42 is now thrown into position to separate the rolls 24, 36 to prevent feeding the wire and the abutment 120 and pressure plate 112 are 120 swung into operative position as determined by the stop pin 118 where they are held by the spring plunger 116. A cemented but as yet unsecured portion of the margin of the 125 upper is folded over the edge face of the sole margin and placed upon the work support with the portion of the upper covering the

edge face of the sole resting firmly against the abutment 120 and the inturned marginal portion of the upper resting upon the pressure plate 112. The portion of upper above 5 the edge of the sole will bridge across the angle between the side of the last and the projecting margin of the sole to a greater or less extent, depending upon proximity of that portion to a staple. The shoe support 10 is then raised by operation of the treadle 94 or by power and the upper is forced by the tool 100 into the angle between the side face of the last and the top face of the projecting margin of the sole, sufficient pressure 15 being applied to secure firm adhesion of the upper on both the top and bottom faces of the sole margin. This is accomplished very effectively by the operator when the power means, brought into action by pressure 20 upon the treadle 96, is employed and the machine may be operated indefinitely by the operator without fatigue and with uniform results. The fact that the upper is held against the shoe sole by the abutment and 25 pressure plate and also yieldingly held by the as yet unset cement, enables the tool 100 to apply very considerable lasting tension to the upper as it is forced by the tool into the angle, the amount of tension depending 30 largely upon the amount of inward pressure applied to the shoe by the operator. The operator therefore has control of the amount of tension which he causes to be applied to the stock and may apply a strong lasting tension 35 when lasting a portion of upper midway between staples and apply less tension as a staple is approached. After lasting a portion of upper and causing it to be securely held by the firm pressure applied to the cemented surfaces, the upward pressure of the work support is released and the work fed along while being held in contact with the abutment 120 and the operation of forcing the shoe against the tool 100 repeated, these 40 operations being carried on successively about the periphery of the shoe properly to last and secure the margin of the upper to the top, edge, and bottom faces of the projecting margin of the sole. 45 Alternatively to the above manner of operation, the abutment and pressure plate may be left in operative position, the operation of bending portions of the upper across the edge face of the sole and against the bottom 50 face may be performed in conjunction with the preliminary driving of staples at various salient points around the periphery, and the lasting may be completed with or without the use of more staples. It is desirable that 55 as few staples as possible be employed, the number used depending upon the nature of the work and being determined by the judgment of the operator. 60 It is also possible to complete the lasting 65 operation step-by-step progressively about

the shoe and in securing the upper at the portion first treated at one side of the shoe while the upper is loosely laid over the last the operator will hold the upper against the top face of the last in the proper position, 70 the margin of the upper lying across or bridging the angle between the side of the last and the projecting margin of the sole and extending beyond the sole if long enough. This portion is folded under the 75 sole and the upper lying across the edge face of the sole is held between the edge of the sole and the abutment by the operator while he raises the support and forces the upper down into the angle by means of the lasting 80 tool. If he finds that too great tension is being applied to the upper and that there is danger of its being displaced relatively to the last, he can relax slightly the force with which he holds it against the abutment and 85 allow the upper to slip relatively to the edge face of the sole and then secure it. At the points secured on the first side of the shoe only light tension is required and the operator may allow the upper to slip between 90 the sole edge and abutment to any desired extent. At the toe, however, and upon the opposite side of the shoe a stronger tension should be produced properly to last the upper and by pressing the shoe against the 95 abutment and employing the power means for raising the work support he may secure a powerful lasting tension and properly last even a refractory upper, staples being used to any extent needed to hold the upper in 100 the angle without cement or in addition to the cement, which when used is caused firmly to adhere by the powerful pressure to which the opposite faces of the projecting flange of the shoe are subjected. 105

The abutment is of utility also in treating uppers which are intended to be trimmed flush with the sole edge. These uppers when applied to the last bridge the angle between the side of the last and the projecting margin of the sole, and are generally ample enough to extend past the edge face of the sole so that they may be clamped between the said edge face and the abutment while 110 the support is being raised manually or by power to force the upper into the angle where it is secured by staples. In this manner, by the friction grip between the abutment and the edge face of the sole, which is always under the operator's control, even 115 short uppers may be tensioned to a greater extent than is practicable or possible when the action of the face 102 of the lasting tool 100 is relied upon solely to tension the upper. After the lasting operation, the shoe 120 may be completed by the attachment of an outersole and heel in the usual manner. In case a fabric upper is employed, the fabric, for example canvas, overlying the top face 125 of the projecting margin of the sole may be 130

relied upon to perform the function of a welt, although, of course, a welt may be provided where additional strength is necessary.

From the above description of the operation of the machine it will be apparent that its use comprises the practice of an improved method of lasting stitch-down shoes, which method is set forth in certain claims herewith presented along with other claims directed to mechanical means by the aid of which the method may be most conveniently practised.

Having fully described my invention, what I claim as new and desire to secure by United States Letters Patent is:—

1. In a machine for lasting shoes which have an outwardly extending upper margin and a sole margin projecting beyond the bottom of the last, the combination of means for supporting the bottom of the sole, means against which the shoe may be pressed to hold the projecting margin of upper against the edge face of the sole, and means, operative while the upper is so held, for wiping the upper down the side of the last toward the sole and against the top face of the projecting margin of the sole to tension the upper.

2. In a machine for lasting shoes in which the margin of the upper is turned outwardly to cover the projecting margin of the sole, the combination of a support for the bottom of the shoe, a presser member for engaging the upper covered top face of the projecting margin, means for engaging a portion of the upper which is bent across the edge face of the sole, and means for effecting relative movement between the presser member and the support in a right line firmly to press the upper into intimate contact with the sole to cause it to be held thereto by cement.

3. In a machine of the class described, a lasting tool formed to force the upper into the angle between the side of the last and the projecting margin of the sole, said tool having a shoe upper engaging end constructed and shaped to hold the upper down and press it positively against the sole margin, of a work support, means for effecting relative movement between the lasting tool and the work support, and means on the work support against which the shoe may be pressed to grip the upper between the edge face of the sole and the last mentioned means.

4. In a machine of the class described, the combination of a tool constructed and shaped to enter the angle between the last and the sole margin and to press the upper against the said margin throughout its lateral extent, a shoe support having a surface parallel to the surface of the tool which lies over the sole margin, an abutment to assist in pressing the upper against the edge face of the sole, and power means for effecting

relative movement between the tool and the shoe support in a direction to cause the said surfaces firmly to clamp the upper and sole margins together.

5. In a machine of the class described, the combination of a tool constructed and shaped to enter the angle between the last and the sole margin and to press the upper against the said margin throughout its lateral extent, a shoe support having a surface parallel to the face of the tool which lies over the sole margin, an abutment to press the upper against the edge face of the sole, manual means for effecting relative movement between the tool and the work support, and power means for further clamping the work between the tool and the support.

6. In a machine of the class described, a work support, means against which the work may be held to force a portion of the margin of the upper against the edge face of the last, means for forcing the upper into the angle between the side face of the last and the projecting sole, and means for securing the upper in the angle.

7. In a machine of the class described, means against which the shoe may be forced by the operator to hold the extending margin against the edge face of the sole with an adjacent portion bridging the angle between the side of the last and the projecting sole, means operable at first manually and then by power to force the bridged upper into the angle, and means arranged to be used optionally to insert fasteners for securing the upper in the angle.

8. In a machine for lasting a shoe which has an outwardly extending margin of upper adapted to be worked against the projecting margin and the edge face of a sole, the combination of a lasting tool adapted to enter the angle between the side of the last and the margin of the sole, a support constructed and arranged to receive the bottom of the margin of the sole and to engage against the upper on the edge face of the sole to hold the same, and means for moving relatively the tool and the support to cause the upper to be forced under tension into the angle and against the margin of the sole.

9. In a machine for lasting a shoe having a sole which projects beyond the bottom of the last and an outwardly extending margin of upper adapted to lie across the edge face of the sole, the combination of a support to receive and support the bottom of a shoe, an abutment operative as the shoe is pushed thereagainst to hold the upper against the edge face of the sole, a lasting tool adapted to enter the angle between the side of the last and the margin of the sole, and means for moving relatively the tool and support to cause the upper to be forced under tension into the angle and against the margin of the sole.

10. In a machine for lasting shoes in which the margin of upper is turned outwardly to cover the projecting margin of the sole, the combination of a support for the bottom of the shoe, a presser member for engaging the upper covered top face of the projecting margin of the sole, means on the support, above the level of support for the greater part of the sole, for engaging a portion of the upper margin, folded inwardly of the shoe beneath the projecting margin of the sole, and means for effecting relative movement between the support and said member to press the margin of the upper against both the top and bottom faces of the sole.

11. In a machine for lasting shoes in which the margin of upper is turned outwardly to cover the projecting margin of the sole, the combination of a support having an inclined face and a staple clenching face, a fastener guiding nozzle having an upper wiping face and the end shaped to enter the angle between the side of the last and the projecting margin of the sole, means for discontinuing the formation of fastenings, a plate arranged for movement into position for raising the level of the inclined face of the work support to provide a pressure surface, means for effecting by power relative movement between the support and nozzle, and an abutment to assist in holding the projecting margin of upper against the edge face of the sole while the upper is being pressed against the top and bottom faces of the sole by the nozzle and pressure plate.

12. In a machine of the class described, the combination of a tool constructed and shaped to enter the angle between the last and the sole margin having a face to press the upper against the said margin throughout its lateral extent and having a vertical outer face, a work support having a face substantially parallel with the margin pressing face of the tool, an abutment having a face substantially perpendicular to the face of the work support and a face parallel with the vertical face of the tool, and means for effecting relative movement between the tool and the work support.

13. In a machine of the class described, the combination of a tool having a face to engage the upper of a stitch-down shoe over the projecting margin of the sole throughout its lateral extent, a work support that is movable to coöperate with the face of the tool to clamp the upper against the projecting margin, and a member coöoperating with the tool and support to embrace the projecting margin and form the upper with square angles at the top and bottom corners of the edge face of the sole.

14. In a machine of the class described, the combination of a tool constructed and shaped to enter the angle between the last

and the sole margin having a face to press the upper against the said margin throughout its lateral extent and having a vertical outer face, a work support having a face substantially parallel with the margin pressing face of the tool, an abutment having a face substantially perpendicular to the face of the work support and a face parallel with the vertical face of the tool, and means for effecting relative movement between the tool and the work support manually or by power at the option of the operator.

15. In a machine for lasting stitchdown shoes in which the upper is to be bent across the edge face of the sole and under the sole margin, the combination of a tool having a face to engage the upper of a stitch-down shoe over the projecting margin of the sole throughout its lateral extent, a work support to coöperate with the face of the tool to clamp the upper against top and bottom faces of the projecting margin, a member coöoperating with the tool and support to embrace the projecting margin to form the upper with square angles at the top and bottom corners of the edge face of the sole, and means relatively to move the tool and the work support and abutment to effect the clamping and forming of the upper to the sole margin.

16. In a machine of the class described, the combination of a lasting tool constructed and shaped to enter the angle between the last and the sole margin and having a face to press the upper against the said margin throughout its lateral extent and having an inner face at a small angle to the vertical, said inner face acting against the side of the last to effect lasting of the upper, a vertically movable work support having a face substantially parallel to the margin pressing face of the tool, an abutment having a face substantially perpendicular to the pressing face of the tool, power means for effecting relative movement of the tool and work support for lasting the upper and pressing the upper against the margin of the sole, and means for simultaneously securing the upper in the angle between the last and the sole margin to hold the upper in lasted position.

17. In a machine of the class described, the combination of a tool constructed and shaped to enter the angle between the last and the sole margin and having a face to press the upper against the said margin throughout its lateral extent, a work support having a face substantially parallel to the pressing face of the tool, an abutment having a face substantially perpendicular to the face of the work support, means for effecting relative movement between the tool and work support to hold the upper of a stitch-down shoe, which has been previously wrapped about the margin of the sole,

firmly against the edge face of the sole and to press it against the top and bottom faces of the margin, and means for securing the upper in the angle between the last and the 5 sole margin.

18. In a machine of the class described, the combination of a tool constructed and shaped to enter the angle between the last and the sole margin and having a face to 10 engage the upper over the said margin throughout its lateral extent and having a vertical outer face, a work support having a surface parallel with the face of the tool, an abutment having a face substantially perpendicular to the surface of the work support and a face parallel with the vertical face of the tool, and means for effecting relative vertical movement between the tool and work support to hold the upper of a 15 stitch-down shoe, which has been previously wrapped about the margin of the sole, firmly against the edge face of the sole and to press it against the top and bottom faces of the margin.

25. 19. In a machine of the class described, the combination of a combined lasting tool and nozzle constructed and shaped to enter the angle between the last and the sole margin, having an inclined face to press the upper against the said margin throughout 30 its lateral extent and having an inner face at a small angle to the vertical, said inner face acting against the side of the last to effect lasting of the upper, a vertically movable work support having a face substantially parallel to the inclined margin pressing face of the tool, an abutment having a face substantially perpendicular to the pressing face of the tool, power means for 35 effecting relative movement of the tool and work support for lasting the upper and pressing the upper against the margin of the sole, and means for simultaneously 40 driving a metallic fastening through the nozzle into the angle to hold the upper in lasted position.

20. That improvement in the art of making shoes, which consists in assembling upon a last an upper and a sole, said upper and 50 sole having marginal portions to one of which cement has been applied, progressively shaping the upper to the last by wiping the upper down over the side of the last, and securing the upper to the sole, as the shaping progresses, by forcing the marginal portion 55 of the upper into close contact with the marginal portion of the sole by a hammer blow to cause firm adhesion of the marginal portions of the upper and sole.

60. 21. That improvement in the art of making shoes which consists in assembling upon a last an upper and a sole having a margin projecting beyond the bottom edge of the last, said upper and sole having marginal 65 portions to one of which cement has been

applied, progressively shaping the upper to the last by wiping the upper down over the side of the last, and progressively securing the upper to the sole by forcing the marginal portion of the upper into firm contact 70 with the marginal portion of the sole simultaneously with the termination of each wiping operation.

22. That improvement in the art of making shoes which consists in applying cement 75 to one of the marginal portions of an upper and a sole which are later to be brought into firm contact with each other, assembling said upper and sole upon a last, progressively shaping the upper to the last by wiping pressure applied to the upper by a tool as it wipes the upper over the side of the last, and progressively securing the upper to the sole by forcing the marginal portion of the upper into firm contact with the marginal portion of the sole through a hammer blow and pressure applied by said tool.

23. That improvement in the art of making shoes which consists in applying cement 90 to one of the marginal portions of an upper and a sole which are later to be brought into firm contact with each other, assembling said upper and sole upon a last, progressively shaping the upper to the last by wiping pressure applied to the upper by a tool as it wipes the upper over the side of the last, and progressively securing the upper to the sole by forcing the marginal portion of the upper into firm contact with the marginal portion of the sole through pressure applied 95 by the tool simultaneously with the termination of each wiping operation.

24. That improvement in the art of making shoes which consists in assembling upon 105 a last an upper and a sole having edge portions, which are later to be brought into firm contact with each other, provided with cement, progressively shaping the upper to the last by wiping pressure applied to the upper by a tool as it wipes the upper over the side of the last, and securing the upper to the sole, as the shaping progresses, by forcing the cemented portion of the upper into firm contact with the cemented portion 110 of the sole through a single hammer blow applied by the tool simultaneously with the termination of each wiping operation.

25. That improvement in the art of making shoes which consists in assembling upon 115 a last an upper and a sole having a margin projecting beyond the bottom edge of the last, said upper and sole having marginal portions to one of which cement has been applied, progressively shaping the upper to the last by wiping the upper down over the side of the last, and progressively securing the upper to the sole by forcing the marginal portion of the upper into firm contact with the marginal portion of the sole and simultaneously inserting a staple 120 125 130

through the cementitious portions of the upper and sole.

26. That improvement in the art of making shoes which consists in assembling upon a last an upper and a sole having a margin projecting beyond the bottom edge of the last, said upper and sole having marginal portions to one of which cement has been applied, progressively shaping the upper to the last by wiping the upper down over the side of the last, and progressively securing the upper to the sole by forcing the marginal portion of the upper into firm contact with the marginal portion of the sole and simultaneously inserting a staple through the cementitious portions of the upper and sole, coincidentally with the termination of each wiping operation.

27. That improvement in methods of making stitchdown shoes which consists in applying cement to the margin of a shoe upper, assembling the upper upon a last having a sole thereon, the margin of which projects beyond the bottom of the last, folding the upper margin across the edge face of the sole with the upper bridging the angle between the side of the last and the projecting sole, and then working successive portions of the upper into the angle while holding the upper in contact with the edge face of the sole with force sufficient to apply to the upper proper lasting tension.

28. That improvement in methods of making stitchdown shoes which consists in applying cement to the margin of a shoe upper, assembling the upper upon a last having a sole thereon, the margin of which projects beyond the bottom of the last, folding the upper margin across the edge face of the sole and against the margin of the sole bottom with the upper bridging the angle between the side of the last and the projecting sole, and then working successive portions of the upper into the angle while holding the upper in contact with the edge face of the sole with force sufficient to apply to the upper proper lasting tension.

29. That improvement in methods of making stitchdown shoes which consists in applying cement to the margin of a shoe upper, assembling the upper upon a last having a sole thereon, the margin of which projects beyond the bottom of the last, folding the upper margin across the edge face of the sole and against the margin of the sole bottom with the upper bridging the angle between the side of the last and the projecting sole, and then working suc-

sive portions of the upper into the angle while holding the upper against the edge face of the sole and against the bottom of the sole to secure the requisite friction to apply to various portions of the upper the proper tension.

30. That improvement in the art of making shoes which consists in assembling upon a last an upper and a sole having a margin projecting beyond the bottom edge of the last, shaping the upper to the last by wiping the upper over the side of the last, securing the upper to the margin of the sole by means of cement, and inserting fastenings at points determined by the operator to insure retention of the upper in lasted condition.

31. That improvement in the art of making shoes which consists in assembling upon a last an upper and a sole having a margin projecting beyond the bottom edge of the last, simultaneously lasting and securing the upper along marginal portions of the sole by a cementing operation, and inserting fastenings at points selected by the operator to insure retention of the upper in cemented relation to the margin of the sole.

32. That improvement in the art of making shoes which consists in assembling upon a last an upper and a sole having a margin projecting beyond the bottom edge of the last, said upper and sole having marginal portions to one of which cement has been applied, progressively shaping the upper to the last by wiping the upper over the side of the last, inserting fastenings at points selected by the operator properly to position the upper with respect to the sole, and completing the lasting of the shoe by cementing operations which secure the upper to the sole throughout the greater part of the marginal portions thereof.

33. That improvement in the art of making shoes which consists in assembling upon a last an upper and a sole having a margin projecting beyond the bottom edge of the last, said upper and sole having marginal portions to one of which cement has been applied, lasting the upper to the sole at points selected by the operator comprising both fastening inserting and cementing operations to retain the upper in proper position relative to the sole, and subsequently cementing the upper to the sole throughout the greater part of the marginal portion thereof.

In testimony whereof I have signed my name to this specification.

ALBERT A. MACLEOD.
